BOTTLE OPENER WITH PIVOTALLY
MOUNTED CAP SKIRT ENGAGING
MEANS

Guy Leonard, Houston, Tex.

Application December 7, 1951, Serial No. 260,433

2 Claims. (Cl. 81—3.3)

1

This invention relates to new and useful improvements in bottle openers and relates particularly to an opener for removing the crown type of cap from beverage bottles.

As is well known, the usual crown type metal cap is applied through a crimping operation to the upper bead of the glass bottle, and it has been found that in the usual type of openers, chipping or breakage of this glass bead will often-times occur. This damage to the bottle results primarily from the fact that the claw or cap engaging member is immovable since improper placement of the bottle relative to such immovable element will cause the same to engage the glass bead as the cap is stripped or removed from the bottle.

It is one object of the present invention to provide an improved bottle opener which will efficiently remove the metallic cap without damage or chipping of the glass bottle bead.

An important object of the invention is to provide a bottle opener wherein the cap engaging element or claw is movably mounted whereby as the cap is removed from the bead of the bottle subsequent engagement of the bead with the cap engaging element will cause said element to move away from said bead rather than engaging and damaging the same, as occurs where the cap engaging element is fixed.

Still another object of the invention is to provide a bottle opener wherein a projection for engaging the central portion of the cap is provided to form a fulcrum point about which the bottle may be moved after the cap engaging element has engaged said cap; fulcruming of the bottle and cap about the projection resulting in the application of a pressure to the central portion of the cap during the removal operation, with said pressure at the central portion of the cap tending to spread the periphery of the cap to assist in the removal operation.

Still another object is to provide an opener of the character described which lends itself to manufacture from metal stampings whereby an extremely simple and efficient opener is provided at a minimum cost.

The construction designed to carry out the invention will be hereinafter described together with other features thereof.

The invention will be more readily understood from a reading of the following specification and by reference to the accompanying drawings forming a part thereof, wherein an example of the invention is shown, and wherein:

Figure 1 is a vertical sectional view of a bottle

opener constructed in accordance with the invention and illustrating the cap engaging element thereof in normal position prior to the insertion of the bottle cap into the opener.

Figure 2 is a similar view with the cap inserted in the opener and prior to removal of the cap,

Figure 3 is a similar view illustrating the cap in the process of removal from the bottle,

Figure 4 is a front elevation of the opener,

Figure 5 is an isometric view of a modified form of the invention, and

Figure 6 is an enlarged detail of the mounting of the cap engaging element of the form shown in Figure 5.

In the drawings the numeral 10 designates a base plate or support member which is adapted to be attached by screws 11 to a wall or other surface A. A pair of outwardly projecting ears or lugs 12 are preferably formed integral with the body and a cap engaging element 13 is adapted to be mounted on a pivot pin 14 between the ears or lugs. The cap engaging element has its outer portion enlarged in transverse width as indicated at 15, and a depending claw 16 is provided at the lower end of the element. The claw 16 has a generally arcuate surface to follow the contour of the bottle and the increased width provides for an amplified gripping area. As will be explained, the claw 16 is arranged to engage beneath the crimped edge of the usual crown type cap C of a bottle B. For limiting the swinging movement of the cap engaging element 13 on its pivot 14, said element has an extension 17 which projects into an opening 18 in the base plate and has a limited movement therein.

The lower portion of the outer face of the plate 10 is recessed, as indicated at 19, and projecting outwardly from this recessed outer surface is a projection or pin 19. The outer end of the pin is preferably rounded and the pin is so located with respect to the pivoted cap engaging element 13 that when the bottle cap C is inserted to have its edge engaged by the claw 16, the projection 19 contacts the central portion of the cap C, as shown in Figure 2. Because the cap engaging element 13 is freely pivoted on its pin it will normally assume the position shown in Figure 1. The bottle cap C may be readily engaged beneath the claw 16 and moved into contact with the projection 19 which also functions as a stop to properly position the bottle cap with respect to the claw.

After the bottle cap C has been engaged with the projection 19 and with the claw 16, as shown in Figure 2, it is only necessary to apply a down-

ward swinging movement to the bottle B. It will be evident that upon such downward swinging of the bottle, the bottle will actually fulcrum about the projection 19. The cap engaging element which has its claw in engagement with the bottle cap edge cannot undergo any downward movement and the claw thus remains substantially stationary to hold the edge of the cap in a fixed plane. As the cap and bottle fulcrum about the projection 19, said projection applies a pressure to the central portion of the cap and the application of pressure at this point tends to flare the periphery of the cap, that is, there is a deformation of the cap which will tend to move the crimped sides of the cap away from the bottle. At the same time, that this pressure is being applied by the projection to the central portion of the cap, the claw 15 is maintaining the upper edge of the cap stationary and the continued swinging movement of the bottle removes the cap from the bead 20 of said bottle, as is clearly illustrated in Figure 3. It is thus obvious that through the combination of pressure applied to the central portion of the cap and the engagement of the claw with the bottle cap edge, an efficient removal of the cap is effected.

In the event that the bead 20 of the bottle has any tendency to engage the claw 15 which might result in damage to the bead, the bead will merely move the claw out of the way. This is true because at the time that the bead engages the claw, said claw is free to swing because the locking action of the claw is produced only through the cap member being simultaneously engaged by the projection 19 and said claw. As soon as the cap member is removed from the bottle, the claw is free to swing and therefore, any subsequent engagement of the bead 20 with the claw will merely move said claw out of the way to obviate any possibility of damage to the bead.

The device is extremely simple in construction and involves only the single movable part, which is the cap engaging element 13. Positioning of the cap for engagement by the element 13 is facilitated by the projection or pin 19, it only being necessary to move the bottle inwardly until it contacts said projection. The projection thus functions not only as a positioning means but as a pressure applying means which assists in the removal of the cap. As above noted, the pivotal mounting of the cap engaging element allows said element to freely swing after the cap is removed to prevent any chipping or breakage of the bead 20 of the bottle.

In Figures 5 and 6, a slightly modified form of the invention is shown wherein the opener is constructed of metal stampings. In this form a base plate 21 is adapted to be attached by screws passing through openings 22 to a suitable wall surface. Upstanding ears 23 which are bent upwardly from the base plate provide a means for pivoting a cap engaging element 24 having an inturned claw 25. The element 24 is formed with outwardly extending pivot lugs 26 which are generally rectangular in shape, as is clearly shown in Figure 6. Each rectangular lug is movable within a double flared opening 27 which is so arranged that swinging movement of the element 24 in both directions is limited. A projection 28 which is comparable to the projection 19 of the first form is provided on the lower edge of the plate 21 and is formed by turning up a portion of the material of which the base plate is constructed. The operation of this form is the same as the operation of the first form of the invention,

the bottle cap C indicated by dotted lines in Figure 5 being inserted so that its central portion is engaged by the projection 28 with its edge engaged by the claw 25 of the element 24. Upon a downward swinging movement of the bottle in the manner above described, the projection 28 applies a pressure to the central portion of the bottle cap C while the claw 25 engages the edge of said cap. The pressure applied by projection 28 tends to flare the sides of the bottle cap and the engagement of the claw completes the removal of the cap from the bottle. Since the cap engaging member 24 is pivoted any subsequent contact of the bead 20 of the bottle with the claw 25 will merely swing the element 24 out of the path of said bead so that damage to said bead is obviated.

In both forms of the invention the projection which engages the central portion of the cap coacts with the claw in applying the necessary pressure to the cap at the desired points to effect an easy removal of the cap. As has been noted, the projection which engages the central portion of the cap also functions as a positioning means which will facilitate the proper positioning of the cap within the opener.

The foregoing disclosure and description of the invention is illustrative and explanatory thereof and various changes in the size, shape and materials, as well as in the details of the illustrated construction may be made, within the scope of the appended claims, without departing from the spirit of the invention.

Having described the invention, I claim:

1. A bottle opener comprising a base plate, spaced lugs on said base plate extending laterally therefrom, a cap engaging element pivotally mounted on said lugs for limited longitudinal swinging movement on said base plate, a cap engaging claw on the outer end of the element for engaging beneath the edge of a crown cap attached to a bead at the mouth of a bottle, a projection extending laterally from the surface of the base plate and spaced from the claw of the pivoted element longitudinally and laterally by a distance which will cause engagement of the projection with the central portion of the cap when the claw element is engaged beneath the edge of said cap to cause an outward flaring of the edge of said cap as said bottle is moved downwardly relative to said cap, said cap engaging element pivoting upwardly and outwardly relative to said bottle as said edge of the cap is flared outwardly so that said cap engaging element is prevented from applying a chipping force to said bead of the bottle while maintaining its engagement beneath the edge of the cap so as to remove the cap from the bottle, said plate having a recess therein in alignment with the space between said lugs, and an extension on the inner end of said cap engaging element extending into said recess and adapted to contact the upper wall of said recess to limit the swinging of said element in a downward direction toward said projection to maintain said cap engaging claw spaced laterally and longitudinally from said projection a distance which will automatically cause engagement of the projection with the central portion when the claw element is engaged beneath the edge of the cap whereby manual manipulation of said cap engaging element is avoided.

2. The structure set forth in claim 1, wherein said base plate has a surface adapted to be positioned against a vertical wall or the like, said

surface being formed on the opposite side of said base plate from said projection and said lugs, and said base plate having an opening therethrough for receiving the shank of a screw whereby said opener can be attached to said vertical wall or the like.

GUY LEONARD.
